UNITED STATES PATENT OFFICE.

SAMUEL SPEED, OF TATUM, TEXAS.

HAMMER FOR OVERHEAD NAILING.

1,225,070.

Specification of Letters Patent.

Patented May 8, 1917.

Application filed November 28, 1916. Serial No. 133,945.

To all whom it may concern:

Be it known that I, SAMUEL SPEED, a citizen of the United States, residing at Tatum, in the county of Rusk, State of Texas, have invented a new and useful Hammer for Overhead Nailing; and I do hereby declare the following to be a full, clear, and exact description of the invention, such as will enable others skilled in the art 10 to which it appertains to make and use the same.

The present invention relates to a hammer for overhead nailing, and has for its object to provide a hammer of this character 15 which embodies novel features of construction whereby a nail can be securely clamped upon the driving end of the head in such a manner as to be properly started upon the initial blow of the hammer, after which the 20 nail can be driven home in the usual manner by successive blows of the hammer.

Further objects of the invention are to provide a hammer of this character which is comparatively simple and inexpensive in 25 its construction, which can be used in the same manner as an ordinary hammer, which admits of the nail being quickly clamped in position after being started or released from engagement with the hammer, and which 30 can be used to great advantage in doing overhead nailing where it is very timesome and difficult to hold the nails in the fingers while starting them.

With these and other objects in view, the 35 invention consists in certain novel combinations and arrangements of the parts as will more fully appear as the description proceeds, the novel features thereof being pointed out in the appended claims.

40 For a full understanding of the invention, reference is to be had to the following description and accompanying drawing, in which:—

Figure 1 is a side elevation of a hammer 45 constructed in accordance with the invention, the lower end of the handle being broken away.

Fig. 2 is a similar view with parts 50 broken away and shown in section to illustrate more clearly certain details of the invention.

Fig. 3 is a front view of the hammer looking directly at the driving end of the head, the lower end of the handle being 55 broken away, and

Fig. 4 is a detached perspective view of the movable clamping jaw.

Corresponding and like parts are referred to in the following description and indicated in all the views of the drawings by the 60 same reference characters.

Specifically describing the present embodiment of the invention, the reference character A designates the head of the hammer, and B the usual handle which has the 65 end thereof fitted within a socket 1 extending transversely through an intermediate portion of the hammer head. A driving end 2 is formed at one end of the head A, while the usual claws 3 are provided at the opposite end of the said head. The side of the driving end 2 which faces toward the handle B is flattened to provide a fixed jaw 4, said jaw being provided with a longitudinal groove 5 which is adapted to receive the 70 shank of a nail C, and which opens through the driving end 2 so that when a nail C is clamped in position the pointed end thereof will project beyond the driving end of the hammer, as indicated by dotted lines on 75 Fig. 1. An angular corner 6 provides a seat at the inner end of the fixed jaw 4, and when a nail C is in position the head thereof abuts against this seat, the projecting edge of the head being received within a 80 recess 7 which is provided at the junction of the seat and fixed jaw.

Coöperating with the fixed jaw 4 to grip the nail C is a sliding jaw 8 which is mounted to move back and forth upon a guide rod 9. The end of the movable jaw 8 which faces the fixed jaw 4 is correspondingly flattened and is provided with a groove 10 which corresponds to the groove 5 of the fixed jaw, the two grooves providing a suitable recess for receiving and properly positioning the shank of the nail C. The inner corner of the sliding jaw 8 is notched at 11 to provide a clearance space for the angular corner 6 of the head, the outer 90 side of the notch being spaced from the seat of the angular corner so as to coöperate therewith to provide a clearance space for the projecting edge portion of the nail head. The guide rod 9 extends loosely 100 through a longitudinal opening 12 in the sliding jaw, and a coil spring 13 which surrounds the guide rod bears against the end of the sliding jaw and normally tends to move it yieldingly toward the fixed jaw 4. 105 110

The inner end of the guide rod 9 is shown as having a threaded engagement with the hammer head A, as indicated at 14^a, while the outer end thereof terminates in a head 5 9^a which is received within a transverse opening formed in an arm 14 which projects laterally from the handle B. This arm 14 may be formed with a threaded stem 15 which is screwed into the handle B, as 10 indicated by Fig. 2. This provides an arrangement of parts which can be conveniently assembled, and which admits of the sliding jaw being easily placed in position or removed therefrom.

15 The inner face of the sliding jaw 8 is flattened at 16 and slides against a flattened guide surface 17 formed upon the hammer head A, said guide surface 17 being arranged at right angles to the fixed jaw 4 of 20 the hammer head. A longitudinal groove 17^a is formed in the flat guide surface 17, while the sliding jaw 8 is provided upon its inner face with a longitudinally extending rib 18 which is received within the groove 25 17^a. The sliding jaw 8 is thus guided and directed in its movements toward and away from the fixed jaw 4 and held against rotation upon the guide rod 9. The outer face of the sliding jaw 8 is cut away to provide 30 a finger piece 19 at the lower end thereof, thereby admitting of the jaw being quickly moved away from the hammer head when placing a nail in position between the jaws or releasing a nail.

35 When it is desired to start a nail in an overhead or other inaccessible position, the nail is inserted in position between the fixed jaw 4 and the movable jaw 8 and the latter permitted to grip the nail, with the pointed 40 end thereof projected beyond the driving end of the hammer head, as indicated by dotted lines on Fig. 1. The coöperating grooves 5 and 10 of the two jaws then receive and engage the shank of the nail in 45 such a manner as to hold the nail against lateral movement, while the head of the nail bears squarely against the shoulder or seat provided by the angular corner 6. The initial stroke of the hammer will then start 50 the nail in the desired manner, the movable jaw 8 being slid away from the fixed jaw to release the nail before the hammer is withdrawn. After the nail has thus been started, it can be driven home in the usual 55 manner by successive strokes of the hammer.

Having thus described the invention, what I claim as new and desire to secure by Letters Patent, is:—

1. A hammer including a head formed

with a driving end having the under side 60 thereof formed to provide a fixed jaw, and also provided with a flattened guide surface, a handle upon one end of which the said hammer head is fitted, an arm projecting laterally from said handle and provided 65 with a guide opening, a guide rod loosely fitted within the said guide opening and screwed into the hammer head, said guide rod being arranged parallel to the flattened guide surface on the hammer head, 70 and a sliding jaw mounted upon said guide rod and having a flattened side which slidably engages the before mentioned guide surface on the hammer head, said sliding jaw coöperating with the fixed jaw to grip 75 a nail to hold it in position for starting upon the initial stroke of the hammer.

2. A hammer including a head formed with a driving end having the under side thereof flattened to provide a fixed jaw, a 80 seat for the head of a nail being formed in the hammer head at the inner end of said flattened surface at right angles thereto, said seat being provided at one side thereof with a recess adapted to receive one side 85 of the nail head, and at the opposite side thereof with a flat guide surface, a handle upon one end of which the said head is fitted, an arm projecting laterally from said 90 handle and provided with a guide opening, a guide rod loosely mounted within said guide opening and screwed into the head of the hammer, said guide rod being arranged parallel to the flat guide surface on the hammer head, a sliding jaw movable toward and away from said fixed jaw for co-operation therewith to grip a nail and hold it in position for starting upon the initial stroke of the hammer, said jaw being slidably mounted upon said guide rod and provided with a flattened side which slidably 95 engages the before mentioned flat guide surface on the hammer head, and being also provided with a cut away portion adapted to coöperate with the before mentioned nail head seat to receive the opposite side of the nail head, and a coil spring surrounding the before mentioned guide rod and interposed between the sliding jaw and the lateral arm projecting from the hammer 100 handle.

In testimony whereof I have signed my name to this specification in the presence of a subscribing witness.

SAMUEL SPEED.
